UNITED STATES PATENT OFFICE.

WILLIAM H. FISHER, OF LOUISVILLE, KENTUCKY.

COMBINED TORCH AND DEVICE FOR OPENING OIL CUPS.

Application filed February 23, 1923. Serial No. 620,834.

To all whom it may concern:

Be it known that I, WILLIAM H. FISHER, a citizen of the United States, residing at Louisville, Jefferson County, Kentucky, 5 have invented certain new and useful Improvements in Combined Torches and Devices for Opening Oil Cups, of which the following is a specification.

This invention relates to torches, particularly those used by enginemen about a locomotive or in railway shops. Enginemen are often required to go about, oiling a locomotive at night, and when they do so, both hands are occupied, one by an oil can, 10 and the other by a torch. Thus whenever an oil cup or journal box has to be opened for inspection or oiling, the torch must necessarily be set down to leave one hand free. Usually the only convenient place to 15 set the torch is on the ground and this often leaves the cup or journal box in darkness.

One of the objects of my invention is to provide a torch with means whereby the covers of oil cups may be conveniently depressed or raised for inspection and oiling, and thus allow the engineman both to hold the light and open the cups, and yet have one hand free to wield the oil can. Another object is to provide a torch with improved 20 means for supporting it in a vertical position when not in use, for instance on the wall of a locomotive cab. Still another object is to provide a torch having the above characteristics which is of simple construction and economical to manufacture. Other 25 objects will be apparent from the accompanying description and annexed drawings, in which:

Fig. 1 is a vertical elevation, partly in 30 section, of a torch constructed according to my invention, and

Fig. 2 is a vertical elevation showing the torch supported on a pair of hooks.

The torch comprises an oil reservoir 10 (preferably in the form of a slender frustum of a cone, so as to constitute a convenient handle), open at the top and provided at the open end with a bushing 11 fastened therein by any suitable method 45 such as soldering. The opening in the bushing is preferably tapered and is threaded as shown at 12 to receive a correspondingly threaded tapered plug or thimble 14. The thimble is provided with a pair of laterally 50 extending arms 15 integral therewith, and 55 a longitudinal hole for the reception of a

tube 16, secured therein with a fluid tight joint. A ball of wicking 17, of asbestos or any suitable material is fastened over the end of the tube in any desired manner, such 60 as by wires 18 and 19 passing through the tube, and in such a way as to form a closure for the tube. When the thimble is screwed up tightly, the threads of the thimble and bushing will bind, due to the taper, and 65 form a perfect oil-tight joint without the use of washers or packing of any kind.

The purpose of the arms 15 is three-fold. The relative proportions of the reservoir and wick tube are such that the arms are 70 disposed above the center of gravity of the torch, even when empty, the arms therefore constituting means by which the torch may be supported in a vertical position when 75 not in use. Fig. 2 shows the torch so supported on a pair of hooks 20 on the wall 21 of a locomotive cab. The arms also enable the bushing carrying the wick tube to be unscrewed easily and tightly screwed up without wrenches or other tools. The main purpose of the arms 15, however, is to constitute implements which may be used to open and close the covers of oil cups and journal boxes. Journal box covers are frequently both heavy and held closed by 80 strong springs and therefore require a considerable force to open them. Consequently the arms 15 are of substantial and rigid construction, the bushing and thimble being made heavy to furnish a firm support. On 85 the other hand it is necessary to make the arms long and slender in order to adapt them to open oil cups which have a small opening and an interior compressible closure.

The torch is normally used in a substantially upright position. When it is desired to light the torch, it is tilted downward for a moment to allow the wicking to become saturated with oil. The wick will hold sufficient oil to burn for a few minutes, and 90 in case it is desired to use the torch for a longer period, it is merely tipped down to replenish the supply of oil in the wick.

It will be understood that the invention is not limited to the details described for the 95 sake of illustration, but includes modifications which fall within the scope of the appended claim.

Having thus described the invention, what is claimed as new and desired to be 100 secured by Letters Patent is:

A combined torch and implement for

opening oil cups comprising in combination, a reservoir of slender frusto-conical form open at its smaller end, a relatively heavy bushing secured in the open end, a relatively heavy thimble adapted to fit in said bushing, a pair of rigid arms extending laterally from the thimble and adapted to be used for

opening oil cups, a fuel tube secured to the thimble, and a wick on the end of the fuel tube.

10

In testimony whereof I hereunto affix my signature.

WILLIAM H. FISHER.
